UNITED STATES PATENT OFFICE.

EVERETT H. BROWN, OF PHILADELPHIA, PENNSYLVANIA.

DESIGN FOR A KNIT FABRIC.

No. 38,414.

Specification for Design.

Patented Jan. 15, 1907.

Application filed December 11, 1906. Serial No. 347,376. Term of patent 7 years.

To all whom it may concern:

Be it known that I, EVERETT H. BROWN, a citizen of the United States, residing in the city of Philadelphia, State of Pennsylvania, have invented a certain new, original, and ornamental Design for Knit Fabric, of which the following is a specification, reference being had to the accompanying drawing, forming a part thereof.

My design is applicable to and intended for the surface ornamentation of that class of

knit fabrics commonly called "eiderdown" fabrics, and the said drawing is a plan view thereof.

I claim—

The ornamental design for a knit fabric, as shown.

EVERETT H. BROWN.
